UNITED STATES PATENT OFFICE.

HIRAM B. COWLEY, OF ENSLEY, ALABAMA.

GUARD MEANS FOR RAILWAY RAILS.

Application filed February 6, 1926. Serial No. 86,525.

- My present invention has to do with means for guarding the rails of railways; and it has for its object to provide a simple and efficient guard means, susceptible of ready installation, and calculated in addition to adequately guarding a rail to contribute to the strength of the rail support and to the holding of the rail against lateral movement under great stress.
- 10 To the attainment of the foregoing, the invention consists in the improvement as hereinafter described and definitely claimed. In the accompanying drawings, forming part of this specification:—
- 15 Figure 1 is a top plan view showing as applied the guard means constituting the best practical embodiment of my invention of which I am cognizant.
- Figure 2 is a transverse section showing 20 my novel guard means as properly arranged relative to a main line rail and sleepers or ties under the same.
- Similar numerals of reference designate 25 corresponding parts in both views of the drawings.
- I show in the drawings a main line rail 1, and also show sleepers or ties 2 positioned in conventional manner below the main line rail.
- 30 Among other elements my novel guard means comprises a base plate 3, preferably of steel, the said plate being provided with apertures for the passage of the shanks of spikes 4 which engage the base of the main rail 1, and being also provided with auxiliary apertures 5, the latter adjacent to one side only of the main line rail 1. The said auxiliary apertures 5 are about one-eighth of an inch nearer the longitudinal center of the rail 35 1 so that when the spikes 4 are driven through the said apertures 5 instead of through the apertures in which the spikes 4 are shown, the main line rail 1 will be positioned closer to the guard rail 6. It will also be noticed in this connection that the apertures 5 extend to a slight extent under the adjacent portion of the base of the main line rail 1. At its longitudinal edge at the opposite side of the guard rail 6, with reference to the main line rail 1, the base plate 3 is spiked to the sleepers or ties as designated by 7, these spikes 7 being arranged approximately as illustrated relative to braces 8 which are preferably of wrought steel. The said 40 braces 8 are riveted to the base plate 3, and are opposed to the side and under the head of the guard rail 6, Figure 2, at the side of the said guard rail 6 remote from the main line rail 1.
- As will be readily understood by comparison of Figures 1 and 2, the guard rail 6 is provided with an intermediate portion in parallelism with the main line rail 1, and is also provided with end portions deflected away from the main line rail 1. It will also be noticed that intermediate of the deflected end portions of the guard rail 6, the base of the said guard rail 6 adjacent the main line rail 1 is sheared off or otherwise removed, so that the portion of the base of the guard rail 6 that is opposed to and abuts against the base of the main line rail 1, is of a less width than the remainder of the base of the guard rail 6. Thus the head of the guard rail 6 is positioned with one edge thereof in close proximity to the head of the main line rail 1 as is desirable in practice.
- The guard rail 6 is riveted at 9 to the base plate 1, and it being remembered that the braces 8 are also riveted to the base plate 1, it follows that my novel guard means is susceptible of being conveniently handled as a unit and is equally susceptible of being readily positioned relative to sleepers or ties and a main line rail and fixed in position 50 with respect to both the sleepers or ties and the main line rail 1, it being understood in this connection that the spikes 4 and the spikes 7 are fixed in the sleepers or ties 2.
- It will also be apparent from the foregoing that the spikes 4 that are driven between the bases of the main line rail 1 and guard rail 6 have their heads disposed above the bases of both rails so that not only the main line rail 1 is directly spiked to the 55 sleepers or ties 2, but the guard rail 6 is also directly spiked to the sleepers or ties, with the result that the strength and durability of the structure as a whole is materially enhanced.
- For the reasons indicated I prefer to employ the specific construction illustrated and hereinbefore described in detail. I do not desire, however, to be understood as restricting myself to the disclosed construction and relative arrangement of the elements, my invention being defined by my appended claims within the scope of which changes in structure and changes in relative arrangement may be made without departure from my invention.
- Having described my invention, what I

claim and desire to secure by Letters Patent, is:

1. Guard means for railway rails, comprising a base plate provided with spike receiving apertures, a guard rail superposed upon and riveted to the base plate and having deflected end portions, said guard rail being co-extensive with said base plate, and braces superposed upon and riveted to the base plate and opposed to and abutting against the adjacent side of the guard rail.
2. Guard means for railway rails, comprising a base plate provided with spike receiving apertures, a guard rail superposed upon and riveted to the base plate and having deflected end portions, said guard rail being co-extensive with said base plate, and braces superposed upon and riveted to the base plate and opposed to and abutting against the adjacent side of the guard rail; the portion of the base of the guard rail intermediate of the said deflected end portion being removed for close positioning of the base of the guard rail to the base of a main line rail.
3. Guard means for railway rails, comprising a base plate provided with spike receiving apertures, a guard rail superposed upon and riveted to the base plate and having deflected end portions, said guard rail

being co-extensive with said base plate, and braces superposed upon and riveted to the base plate and opposed to and abutting against the adjacent side of the guard rail; the base plate being provided adjacent to the spike receiving apertures remote from the guard rail with auxiliary spike receiving apertures that extend closer to the longitudinal center of the base plate.

4. Guard means for railway rails comprising a base plate with two spaced longitudinal sets of apertures for the passage of spiked shanks, a guard rail riveted on said base plate and having deflected end portions and also having the intermediate portion of its base removed in part between the said deflected end portions, said guard rail being co-extensive with said base plate, and braces riveted to the base plate and arranged at the side of the guard rail remote from said reduced base portion; the base plate being further provided at points adjacent to the said spike receiving apertures of the set remote from the guard rail with auxiliary spike receiving apertures that extend nearer to the longitudinal center of the base plate and are adapted to extend partly below the webs or base of a main line rail.

In testimony whereof I affix my signature.

HIRAM B. COWLEY.
